CLAIM

The ornamental design for a lighting fixture, as shown and described.

DESCRIPTION

FIG. 1 is an isometric view of a lighting fixture showing our design from the bottom and the front side;

FIG. 2 is a bottom plan view of the lighting fixture illustrated in FIG. 1;

FIG. 3 is a top plan view of the lighting fixture illustrated in FIGS. 1 and 2;

FIG. 4 is a front elevation view of the lighting fixture illustrated in FIGS. 1 through 3;

FIG. 5 is a rear elevation view of the lighting fixture illustrated in FIGS. 1 through 4; and,

FIG. 6 is a right side elevation view of the lighting fixture illustrated in FIGS. 1 through 5, the left side being a mirror image thereof.

The broken lines in the drawing form no part of the claimed design.
